INTERNAL COMBUSTION ENGINE

Walter A. Schweiger, La Crosse, Wash.

Application November 29, 1937, Serial No. 177,130

1 Claim. (Cl. 123—13)

The present invention relates to improvements in internal combustion engines of rotary type, and consists broadly of a rotor geared to a plurality of rotary abutments capable of timing the compressing, firing and the exhausting of the gases therefrom.

The principal object of the invention is to provide a rotary motor having a rotor and a plurality of rotary abutments geared to said rotor, which rotor embodies opposed arcuate segments or blocks utilizing a continuous displacement principle, by the displacement of their size as they pass from one chamber to the next of the engine, thus avoiding the necessity of using piston seals as in other types of engines.

Another object of the invention is the provision of an engine of this character that due to the displacement principle, the rotary abutments are not required to and do not contact the blocks of the rotor. Therefore, complications at these points are avoided thus allowing said abutments to turn freely regardless of the forces against them, and thus in a great measure reducing wear and noise in the operation of these parts.

25 A further object of the invention is the provision of an internal combustion engine of rotary type which employs a rotor having opposed blocks, one of which is closed and the other provided with by-pass chambers, the closed block continually producing compression in front and continuously passing behind it due to the displacement principle set forth.

A still further object of the invention is to provide a rotary engine in which the intake and the exhaust utilizes the principle of passing the fuel and the exhausted gases through the housing and into the rotor and blocks, thus as the combustion charges continually follow the rotor block or blocks, no ignition is necessary after the engine is once started, whereby the intake of fuel is greatly aided by centrifugal force and the exhausted fuel is forced out by said block or blocks of the rotor.

An additional object of the invention is to provide a rotary engine in which the combustion passes the block of the rotor to the rear thereof and will be continually fed by the compressed charges passing the same, thus as the compressed charges continually follow the rotor block or blocks no ignition is necessary after the engine is once started.

Other objects and advantages will be apparent during the course of the following description.

In the accompanying drawings forming a part of this specification and in which like numerals are employed to designate like parts throughout the same,

Fig. 1 is a front elevation of the motor with the front plate removed from the housing, and

disclosing the rotor and rotary abutments geared to the rotor for synchronized movement;

Fig. 2 is an enlarged plan section of the rotor, showing the by-passes formed in one block thereof, the section being indicated by the line 5 2—2 in Fig. 6;

Fig. 3 is a greatly enlarged vertical section of the engine, showing the various coating parts thereof, the section being indicated by the line 10 3—3 in Fig. 1;

Fig. 4 is a diagrammatic view illustrating an advanced position of the rotor to that shown in Fig. 1;

Fig. 5 is a view similar to Fig. 4, showing the rotor and associated abutments in a still further 15 advanced position to that shown in Fig. 4; and

Fig. 6 is a detail partly in section of the rotor per se, and further illustrating the by-pass section of the fuel intake and exhaust block of said 20 rotor.

In the accompanying drawings, I have shown the preferred form of my invention as applied to a rotary engine, however, I wish it understood that the principle may be readily applied to meters and pumps, as the continuous displacement of the rotor blocks produces a constant and invarying intake and exhaust action throughout the entire revolution of the rotor, thus providing a perfect even flow of substance 25 in a pump or meter as well as a perfectly even flow in a power unit. When utilized as a meter, the continuous displacement of the piston blocks of the device offers a positive and thus an accurate measurement of fluids, while at the same 30 time it turns freely due to the intake and the exhaust chambers being arranged on opposed 35 sides of the rotor blocks.

Referring in particular to the drawings, and especially to Figs. 1 and 2 thereof, the improved 40 engine comprises a casing or housing 8 having a centrally disposed rotor chamber 9 and a rotor 10 mounted therein on a shaft 11, said rotor shaft 11 being mounted in suitable anti-friction bearings 12 and 13 carried by the housing sections 8, as clearly disclosed in Fig. 3.

The housing 8 is also provided about its periphery with a plurality of abutment chambers 14, 15 and 16 communicating with the rotor chamber 9. Mounted in these abutment chambers is a plurality of rotatable substantially semi-circular disk-like abutments 17, 18 and 19, respectively, mounted upon shafts 20, 21 and 22, which shafts are mounted in suitable anti-friction bearings 23 and 24.

The rotor 10 is geared to the rotatable abutments 17, 18 and 19 by means of main driving gears 25 rotatable with said rotor and meshing with gears 26, 27 and 28 carried, respectively, by the shafts 20, 21 and 22, whereby the rotary 55

movement of said abutments is synchronized with the rotary movement of the rotor 10.

The rotor shaft 11 is keyed to the rotor sleeve by means of a plurality of keys 29, and said shaft 5 is mounted in suitable bearings 30 and 31 carried by the housing 8, said shaft being sealed at one end by means of a packing gland 32 carried by the housing and at its opposite end by means of a cap member 33.

10 The rotor 10 is provided with concentric channels 34 and 35 positioned in opposite faces thereof, and these channels communicate, respectively, with the exhaust line 36 and the fuel intake line 37, through the medium of ports. (See Fig.

15 3.) The rotor is also provided with diametrically opposed hollow blocks or heads 38 and 39, the head 38 being provided with chambers 40 and 41 communicating, respectively, at their inner ends, with the channels 34 and 35, and having their

20 outer ends and sides closed, but open to the rotor chamber 9, along the edge portions of the head, the opening of the chamber 40 being along one edge portion, while the opening of the chamber 41 is along the opposite edge portion, as clearly

25 disclosed in Figs. 2 and 6, and said chambers 40 and 41 are separated by means of a diagonally disposed partition 42. The block or head 39 may also be provided with these intake and exhaust chambers, if desired.

30 As disclosed in Fig. 1 of the drawings, the rotor chamber 9 consists of a series of chambers 43, 44 and 45 in which intake, exhaust, firing and compression cycles take place. In the position shown, the abutment chamber 14 has just been 35 exhausted and is about to start taking in an explosive charge of air and gas, which is in neutral position. The rotor chamber 43 is taking a mixture of gas and air, and the rotor chamber 44 is shown with a charge of gas therein and a charge 40 of expanded gas ready to be exhausted therefrom. The abutment chamber 15 is filled with an expanded charge ready for exhaust and a charge is being fired in the pocket formed between the rotor block 39 and the abutment 18. 45 The chamber 45 is filled with a compressed mixture of air and gas and the abutment chamber 16 is filled with a fresh mixture of gas and air.

It will be noted that the rotor heads or blocks 50 38 and 39 form a sliding rotary fit within the rotor chamber 9 and that the concentric inner faces between these blocks contact the peripheral faces of the rotary abutments 17, 18 and 19, as clearly disclosed in Figs. 1, 4, and 5.

In the diagrammatic view shown in Fig. 4, the 55 block 38 of the rotor is indicated in an advanced stage of its continuous intake and exhaust cycles and the block 39 is in the central stage of its firing stroke in chamber 45. The remaining compressed mixture in front of said block 39 has 60 passed into the chamber formed by the rotary abutment 19 and is being compressed along with the mixture already existing in this chamber. A small portion of this mixture will pass into the next chamber 43 through the gap formed between the abutment 19 and the block 39, as shown by the arrow, when the block 39 and abutment 19 are in the position shown. However, they are in that position momentarily, as will be apparent, and the gap, as well as the gap shown 70 between the block 38 and the abutment 17, will exist only for an instant, while the engine is running.

In the diagrammatic view shown in Fig. 5, the rotor block 38 is indicated in another stage 75 of its continuous intake and exhaust cycles, and

said block 39 is still shown in its firing stroke, but in a position to close the chamber 16 of the abutment 19, and has begun its compression stroke in chamber 43. High compression now exists in the closed chamber of the rotary abutment 19 and the latter chamber will immediately open into the present firing chamber 45, thus adding to the explosion of the firing charge in said chamber 45. In this connection it will be noted that the rotary abutment discs 17, 18 10 and 19 act as abutments to produce the same results as cylinder heads of a reciprocating engine, but allow the blocks 38 and 39 of the rotor to pass through the cut-out sections thereof when all parts are in synchronized motion by 15 means of master gear 25 and the gears 26, 27 and 28 meshing therewith.

The cycles above described continue as the rotor is rotated and the intake charges enter the channel 35, from the intake line 37 and the exhaust is carried out from the outlet channel 34 20 through the exhaust line 36, as clearly shown in Figure 3.

A spark plug 46 is mounted in the housing and projects into the chamber 45 to start the engine, 25 however, as soon as the rotor has received a few impulses from the exploding gases this may be dispensed with, as hereinbefore explained.

It will, therefore, be obvious from the foregoing description that I have produced an engine 30 of rotary type that embodies comparatively few working parts, that is positive in its action and that does not require packing rings or spring controlled elements in its operation, thus making an engine of this character very economical 35 to manufacture and assemble and adding greatly to the life thereof.

It is to be understood that the form of my invention herewith shown and described is to be taken as a preferred example of the same and 40 that various changes relative to the material, size, shape and arrangement of parts may be resorted to without departing from the spirit of the invention or the scope of the subjoined claim. 45

Having thus described my invention, I claim:

A rotary engine comprising a housing having a centrally disposed chamber therein and chambers disposed circumferentially about the central chamber and communicating therewith, said housing provided with intake and exhaust ports 50 opening into the central chamber, a rotor within the central chamber and having annular channels therein, one on each side face and communicating respectively with the intake and exhaust ports, diametrically opposite hollow heads integral with the rotor, a partition for at least one head and disposed diagonally therein to provide an intake chamber and an exhaust chamber having open inner ends communicating respectively with the intake and exhaust channels, said intake and exhaust chambers having closed outer ends and sides and each provided with an opening, with the opening of the intake chamber disposed along one edge portion of its head and the opening of the exhaust chamber disposed along the opposite edge portion, substantially semi-circular disk-like abutments within the circumferentially arranged chambers and geared to the rotor for synchronized rotation thereof, and the rotor and abutments being so constructed and arranged with respect to each other that the abutments will be engaged with the rotor between the heads at certain times and the heads are spaced from the abutments at all times. 65

WALTER A. SCHWEIGER. 75
